UNITED STATES PATENT OFFICE

HANZABURO HARASE, OF LOS ANGELES, CALIFORNIA

ELECTRIC COLOR RAY SIGN

Application filed January 27, 1931. Serial No. 511,508.

This invention relates to improvements in electric luminescent and color ray signs, and its objects are to provide such luminescent signs having, with a given electric luminescent element, a greater brilliancy and color effect than has been attained heretofore in electric signs, and to provide an electric sign which is easy on the eyes, which has no glare, and which is well adapted to compel the attention of the observer.

Other objects and advantages may appear in the subjoined detail description.

The drawings exhibit a device embodying the features of this invention and show a few modifications thereof.

In the drawings: Figure 1 is a perspective view of the device showing the front thereof. Fig. 2 is a perspective view of the base and luminescent elements mounted thereon. Fig. 3 is a perspective view of a modified form. Fig. 4 is a sectional detail view of a refracting member of the device. Fig. 5 is a plan view of the device with the top wall removed, showing the arrangement of the refracting elements and the luminescent elements. Fig. 6 is a perspective view of the device arranged in the form of an alphabetical letter. Fig. 7 is a diagram showing the electrical switch elements.

Referring in detail to the drawings, my improved device consists of a frame 11 which is mounted on a base 12, wherein may be mounted a sign-flasher switch 17 and a transformer 25, which are used to control the electric energizing current to the neon tubes 13, projecting upwardly from the base.

For the purpose of illumination, the neon tubes as shown may be used, or any common or colored electric bulbs may be used. For the purpose of refracting and diffusing the light, and to increase the brilliancy of illumination as viewed from any suitable angle, I provide the refracting tubes 14, which consist of small tubes of glass, filled or partly filled with water, clear water or colored water, in any preferred combinations of colors. The tubes may be colored and of different alternating colors, and filled with clear or colored water. Fig. 4 shows a glass tube 14, filled with water.

A channel iron 16, 50

preferably of sheet metal, supports tubes 14 at the top and bottom. Tubes 14 are sealed after filling with the liquid. Tubes 14 are spaced from neon tubes 13, at such distance that they may be brilliantly illuminated 55 thereby.

In the diagram as shown in Fig. 7, the electrical energizing elements for the illuminating elements are shown, and these may be disposed within the base 12, or may be within a separate housing (not shown). A rotary flasher switch 17, and an electric motor 18, are supplied with current from any suitable power line terminals 19, controlled by switch 20. Leads 21 extend from switch 20 to electric motor 18, and leads 22 extend from switch 20 to flasher switch 17. The flasher switch is driven by motor 18 through gears 23. Primary leads 24, in circuit with contacts 29, of flasher switch 20, extend to transformers 25, and secondary leads 26 extend from transformers 25 to neon tube sockets 27. The contacts 28, of flasher switch 20, are arranged so that tubes 13 are electrically energized singly or simultaneously, the order 75 of energizing being, of course, variable by suitable arrangement of the flasher switch contacts 28. It may be noted that the flasher switch is in the primary circuit. Hand actuated switches may be substituted in certain 80 cases, for the automatic control as set forth.

In the modified form shown in Fig. 6, the arrangement of refracting tubes 14 simulates the form of the alphabetical letter H. The illuminating neon tube 13 will be connected 85 to high potential leads as in the preferred form. In either form, to obtain the most efficient illuminating, blending and color effects, the illuminating neon tubes are disposed parallel with the refracting tubes 14. 90

Any suitable sign-flashing switch may be considered the equivalent of switch 20.

Stencil or other advertising characters (not shown), may be placed adjacent to and at the front or rear of tubes 14. As a variation, plain or colored glass rods (not shown) may alternate with the tubes that are filled with liquid. Another variation would be to fill alternate tubes with irregular broken bits 100

of glass of different colors as a substitute for the liquid.

The essence of my invention comprises the combination with electric luminescent and colored tubes, of refracting tubes positioned adjacent to the electric tubes, and colored and filled with a colored liquid or filled with broken bits of colored glass whereby the luminescent rays emanating from the electric tubes, are enhanced, made more brilliant, and diffused or refracted, and whereby electric signs may be made more brilliant, more ornamental and more attention-attracting than heretofore.

15 The variations set forth herein, including colored tubes, colored water, clear water, and broken bits of glass for the tube filler, may all be considered as practical equivalents in refracting the light, and in making the sign ornamental.

20 What is claimed is:

1. The combination with a plurality of differently colored and intermittently energized electric illuminating elements, of a plurality of light-refracting tubes disposed adjacent to the illuminating elements, and a liquid content in each light-refracting tube, certain of the liquid contents being clear and others of different colors.

25 2. The combination with a base and a supporting frame, of a plurality of differently colored and intermittently energized electric illuminating elements supported by the base and within the frame, and a plurality of liquid-filled light-refracting tubes disposed in the frame and adjacent to the illuminating elements.

30 3. The combination with a plurality of differently-colored and intermittently energized electric illuminating elements, of a plurality of clear-colored and differently colored glass tubes disposed in front of and adjacent to the electric illuminating elements, the clear glass tubes alternating with the colored tubes, and differently-colored light-refracting elements disposed in the glass tubes.

35 4. The combination with liquid-filled and differently colored glass tubes for refracting light rays, of a plurality of differently-colored and intermittently energized electric luminescent tubes disposed adjacent to the refracting tubes.

40 5. The combination with liquid-filled and differently colored glass tubes for refracting light rays, of a plurality of differently colored and intermittently energized electric luminescent tubes disposed adjacent to and extending parallel with the refracting tubes.

45 6. The combination with liquid-filled and differently colored glass tubes for refracting light rays, of a plurality of luminous tubes disposed adjacent to and extending parallel with the refracting tubes, and means for causing illumination of the luminous tubes

separately for producing different color effects.

7. The combination with liquid-filled and differently colored glass tubes for refracting light rays, of a plurality of luminous tubes disposed adjacent to and extending parallel with the refracting tubes, means within said tubes for emitting various colors and tints, and means for causing illumination of the luminous tubes separately for producing different color effects.

75 8. The combination with liquid-filled and differently colored glass tubes disposed vertically for refracting light rays, of a plurality of luminous tubes disposed adjacent to and extending parallel with the refracting tubes, and means for energizing the luminous tubes separately and intermittently.

80 9. The combination with transparent tubes for refracting light rays, and means within the refracting tubes for emitting different colors and tints, of different colored glass bars alternating with the refracting tubes, and a plurality of different colored luminous tubes disposed adjacent to and extending parallel with the refracting tubes and bars.

85 10. The combination with plain colored glass bars for refracting light rays, and different colored glass bars alternating with the plain colored bars, of a plurality of different colored luminous tubes disposed adjacent to and extending parallel with the glass bars, and means for energizing the luminous tubes.

90 11. In an electric luminescent sign, the combination with a frame, a base supporting the frame, a plurality of sockets disposed in the base, neon tubes mounted in the sockets and extending upwardly in the frame, and a plurality of refracting tubes within the frame and adjacent to the neon tubes, of electric transformers adjacent to the neon sockets, high potential conductors leading from the transformers to the neon sockets, a rotary flasher switch adjacent to the transformers, leads extending from the flasher switch to the transformers, an electric motor actuating the rotary flasher switch, a control switch, primary leads extending from the control switch to the motor and flasher switch, and gears arranged whereby the motor actuates the flasher switch.

100 12. In an electric sign, the combination with neon tubes, of a frame enclosing the neon tubes, and a plurality of light refracting tubes disposed adjacent to the neon tubes, the light refracting tubes being supported by the frame and in parallel relation to said neon tubes.

105 In testimony whereof I hereunto affix my signature.

110 HANZABURO HARASE.
